UNITED STATES PATENT OFFICE.

ARTHUR C. MATHEWSON, OF LISLE, NEW YORK.

TELLTALE BOTTLE.

1,111,483.

Specification of Letters Patent. Patented Sept. 22, 1914.

Application filed March 5, 1914. Serial No. 822,674.

To all whom it may concern:

Be it known that I, ARTHUR C. MATHEWSON, a citizen of the United States of America, residing at Lisle, in the county of Broome and State of New York, have invented certain new and useful Improvements in Telltale Bottles, of which the following is a specification.

This invention relates to improvements in non-refillable bottles, designated as a telltale bottle.

The primary object of the invention is to provide a bottle adapted especially for holding liquids such as liquors and which automatically registers upon being emptied and upon a refilling thereby indicates that is has once been emptied and thereafter refilled.

A further object of the device is to provide in a liquid receptacle a tell-tale member retaining its position at the latest lowest level assumed by the contents and which is incapable of alteration from the exterior.

A still further object is to provide a telltale bottle with a float means capable of lowering but securely locked against movement toward the mouth of the bottle and which remains suspended during the pouring operation but assumes its locked position at the liquid level upon a return of the bottle upright.

A further provision is devised whereby through a means providing a tortuous passage for the fluid it is impossible to enter a tampering device therein to retain the telltale member against operation.

These objects therefore are for the purpose of preventing a refilling of a once emptied receptacle without such fact that the contents is a refilling being at once readily apparent to an observer of the bottle such as the prospective purchaser.

With these general objects in view and others that will appear as the nature of the invention is better understood, the same consists in the novel combination and arrangement of parts hereinafter fully described, illustrated in the accompanying drawings and pointed out in the appended claims.

In the drawings forming a part of this application and in which like designating characters refer to corresponding parts throughout the several views:—Figure 1 is a central vertical longitudinal section of a bottle having the invention provided therein.

Fig. 2 is a vertical transverse sectional view

of the tell-tale member and its suspending spring detached. Fig. 3 is a horizontal transverse sectional view taken upon line 3—3 of Fig. 1. Fig. 4 is a horizontal transverse sectional view taken upon line 4—4 of Fig. 1, but showing the side racks as being U-shaped in cross section, and Fig. 5 is a detail view of a section of one of the racks.

Referring more in detail to the drawings, the bottle 10 is illustrated as provided with a hollow disk 11 closed at its top and positioned in the neck 12 thereof and having longitudinal corrugations or passages 13 adjacent the inside surface of the neck for allowing fluid to enter and flow from the bottle. The four rack members 14 are secured to the bottom edge of this disk being preferably united at their bottoms 15 and seated upon the bottom of the bottle. Between the racks 14 is suspended the four armed spider 16 having notches 17 at the end of each arm adapted to fit over the said racks and prevented from moving upwardly by the teeth thereof while said teeth are provided with top ledges 18 at the end of each tooth and upon which the spider arms may rest, it being noted that said spider is formed of resilient material.

A hollow float 19 is suspended from the center of the spider by a universal ball connection 20 while a ball weight 21 is mounted within the chamber 22 of said float and adapted to move by gravity to either side of the chamber and thereby tilt the float in that direction for engaging the rack. An inverted saucer 23 is secured to the bottom of said float and affords an annular side flange 24 which will engage with the faces 18 of the rack teeth when the bottle is tilted in the pouring operation, the connection of the ball 20 with the float having a conical neck to insure a tilting of the float when inverted, said neck passing through the central opening 16' of the spider.

While the racks disclosed in Fig. 1 are formed of single bars, it may be advantageous to employ U-shaped angle bars in the formation of said racks as clearly disclosed at 25 in Fig. 4. It is also to be noted that to prevent any tampering of the tell-tale mechanism, the neck of the bottle is provided above the disk 11 with a hollow casing 26, the top of which is secured within the neck as by the sealing collar 27 or in any other desired manner and is provided with inwardly struck tongues 28 in both the top

and sides thereof and thereby allowing liquid to pass either into or out of the bottle while the bottom 29 of said member is of solid formation and preferably mounted 5 upon the top of the disk 11 and if desired may be permanently secured thereto. Leaf springs 30 are secured to the outer side of each of the racks 14 and are inserted within the bottle through the neck thereof with said 10 racks and at which time they are in flat engagement therewith but assume their normal positions by reason of their own resiliency after insertion as disclosed in Fig. 1. It is thought that the complete operation 15 of the device will be at once apparent. With the bottle filled with liquor when it is sold, the spider will be in substantial engagement with the lower edge of the disk 11 and upon using some of the liquid, the float 19 drops 20 to the level when the bottle is again placed in upright position and being allowed to do so by the ratcheting downward movement of the spider 16, which latter rests upon the faces 18 of the rack teeth and is prevented from 25 any return or upward movement by engaging the lower faces of said teeth. Upon tipping the bottle to either side during the pouring operation, the float is tilted upon the ball suspension 20 and engages the 30 flange 24 with the top faces 18 of some of the adjacent rack teeth and whereby the float member is prevented from lowering until the bottle has again been placed in its upright position and whereupon the float 35 drops to the level of the contained liquid.

The spring members 30 prevent any removal of any part of this device while the only passages for the fluid being through the side corrugations 13 and the openings of 40 the top casing 26, it is impossible to insert any tampering implement to retain the float from lowering so that the registering of the last lowest position of the liquid is insured.

While the forms of the invention herein 45 shown and described are what are believed to be preferable embodiments thereof, it is nevertheless to be understood that minor changes may be made in the form, proportion and details of construction and material 50 without departing from the spirit and scope of the invention as set forth in the appended claims.

Having thus described the invention and in what manner the same is designed for 55 use, what I claim as new and desire to secure by Letters Patent of the United States is:—

1. A device of the class described comprising a receptacle, a quadruple rack positioned therein, means for preventing the removal 60 of said rack, a spider mounted for ratcheting engagement with the teeth of said rack, a hollow float having universal connection with said spider, and a ball weight posi-

tioned for free movement within said float, said float being adapted for engagement 65 with said rack upon lateral movement of said float.

2. A device of the class described comprising a receptacle, a quadruple rack positioned therein, means for preventing the removal 70 of said rack, a spider mounted for ratcheting engagement with the teeth of said rack, a four armed spider spanning said rack, the teeth of said rack having horizontal bottom faces, a hollow float centrally suspended for 75 free movement from said spider, a ball weight within said float, and an annular projecting flange upon the bottom of said float and adapted for engaging the upper faces of the rack teeth. 80

3. A tell-tale bottle comprising a receptacle, a rack positioned therein, teeth upon said rack having horizontal top and bottom faces, a spider engaging said rack and adapted for ratcheting movement there- 85 against in only one direction and having a central opening, a hollow float, a conical neck upon said float extending through said opening and a ball suspending means upon said neck above said spider. 90

4. A tell-tale bottle comprising a receptacle, a rack positioned therein, teeth upon said rack having horizontal top and bottom faces, a spider engaging said rack and adapted for ratcheting movement there- 95 against in only one direction and having a central opening, a hollow float, a conical neck upon said float extending through said opening and a ball suspending means upon said neck above said spider, a ball weight 100 within said float, a projecting annular flange upon the bottom of said float and adapted to engage the top faces of said teeth upon a tilting movement of the bottle.

5. A tell-tale bottle comprising a recep- 105 tacle, a rack positioned therein, teeth upon said rack having horizontal top and bottom faces, a spider engaging said rack and adapted for ratcheting movement there- 110 against in only one direction, a hollow float, a universal ball suspending means between said spider and float, a ball weight within said float, a projecting annular flange upon the bottom of said float and adapted to engage the top faces of said teeth upon a 115 tilting movement of the bottle, a disk within the neck of said bottle and secured to said rack and having side corrugations therein, and a perforated hollow casing positioned above said disk. 120

In testimony whereof I affix my signature in presence of two witnesses.

ARTHUR C. MATHEWSON.
